(57) **CLAIM**

The ornamental design for a belt buckle, as shown and described.

DESCRIPTION

FIG. 1 is a perspective view of a belt buckle, showing my new design;

FIG. 2 is another perspective view thereof, shown in a detached position;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The portions of the belt buckle shown in broken line form no part of the claimed design.
